UNITED STATES PATENT OFFICE.

HENRY ALBERT FLEUSS, OF THATCHAM, ENGLAND, ASSIGNOR TO THE PULSOMETER ENGINEERING COMPANY, LIMITED, OF READING, ENGLAND.

PUMP FOR EXHAUSTING AIR AND GASES.

1,382,184.

Specification of Letters Patent. Patented June 21, 1921.

Application filed January 4, 1919. Serial No. 269,693.

(GRANTED UNDER THE PROVISIONS OF THE ACT OF MARCH 3, 1921, 41 STAT. L., 1313.)

To all whom it may concern:

Be it known that I, HENRY ALBERT FLEUSS, a subject of the King of Great Britain, residing at Dunstan Lodge, Thatcham, Berks, 5 England, have invented new and useful Improvements in Pumps for Exhausting Air and Gases, for which I have filed an application in Great Britain dated June 5, 1917, of which the following is a specification.

10 This invention relates to improvements in pumps for exhausting air and gases of the cylinder and piston type in which the cylinder cover forms the pump valve, or in which a fixed cover has a central valve, and the 15 top of the piston is coned and corresponds in shape to the under surface of the pump valve, or the top of the piston is in the form of a double cone corresponding in shape to the cylinder cover and its valve, and in which 20 the oil is forced into the cylinder by a ram or the like.

According to this invention the piston is operated by a piston rod which passes through a stuffing box in the pump valve 25 and has upon it, above the cylinder cover, a slide for actuating a ram for supplying oil to the cylinder close to the under side of the pump valve. The slide and mechanism for actuating the ram together with 30 the top of the cylinder are surrounded by a casing from which the air is exhausted by another pump.

The ram for pumping the oil works in a cylinder having ports leading into another 35 cylinder surrounding the first and containing oil, the ports being opened and closed by the ram. Attached to the ram is a stem which may be in two parts abutting one another endwise, and which has a spring tending 40 to hold the ram in such a position that the ports are open. The ram is reciprocated in the cylinder by means of a bell crank lever which engages with the stem and is actuated by the slide on the piston rod, the 45 parts being so adjusted that the oil is pumped into the cylinder as the piston nears the pump valve. In the passage between the ram cylinder and the pump cylinder is a non-return valve, and the oil passes into the pump

cylinder through another valve controlled 50 by a spring which is powerful enough to hold it upon its seat if the vacuum in the apparatus is broken. The oil cylinder is fitted with filling and levelling plugs.

A slot may be made in the wall of the 55 pump cylinder extending from one of the air inlet or suction ports to the blind end of the cylinder to prevent the formation of a pocket of air or oil; or the piston may be provided with an automatic valve to allow 60 of the passage of air through it.

The piston rod may pass out of the casing through a stuffing box, or it may be reciprocated from a revolving shaft by means of a connecting rod, which shaft passes through 65 packing in the walls of the casing.

The annexed drawings show a pump made in accordance with this invention. Figure 1 is a section and Fig. 2 is an elevation. Fig. 3 shows details of a valve through which 70 oil is fed into the pump cylinder.

a is the pump cylinder in which works a piston *b* coned at *b*¹ and corresponding in shape to the under surface of the pump valve *c*. A piston rod *b*² connected to the 75 piston *b* passes through a stuffing box *c*¹ in the pump valve *c* and extends outside the casing through a stuffing box *d*. The travel of the piston *b* is such that at the end of its stroke it is in close proximity to the valve 80 *c* but does not lift it from its seat. Upon the piston rod is a slide *e* which, as the piston reciprocates, engages with one arm *f* of a bell crank lever pivoted at *f*¹ the other arm *f*² of which depresses the stem *g* of a ram 85 *g*¹ reciprocating in a cylinder *g*². On the stem *g* is a spring *g*³ which constantly tends to raise the ram *g*¹ in the cylinder *g*² and so open the ports *g*⁴ in the walls of the cylinder *g*². The stem *g* and the cylinder *g*² are 90 contained in another cylinder *h* which is supplied with oil through a plug *h*¹. At the top of the cylinder *h* is another plug *h*² which is opened when the cylinder is filled in order to let it be ascertained when the 95 level of the oil reaches the plug hole. A passage *j* leads from the bottom of the cylinder *g*² to the top of the pump cylinder in

proximity to the valve *c* and in this passage is a non-return valve *k*. The oil passes from the passage *j* into the cylinder *a* through a valve *l* (see Fig. 3) controlled by a spring *l'* which is powerful enough to hold it upon its seat if the vacuum in the apparatus is broken. In order to prevent a pocket of air or oil being formed at the bottom of the cylinder *a* a slot *m* is made in the walls 10 of the cylinder extending from the base of the cylinder to one of the inlet ports *n*. The piston rod *b*², slide *e* and both arms *f* and *f'*² of the bell crank lever are all contained within a casing *o* from which the air is exhausted. *p* is a pipe leading to the inlet ports *n* and *q* is another pipe leading to a second pump by which the air is exhausted.

In operation, as the piston *b* reciprocates in the cylinder *a* the slide *e* comes into contact with the arm *f* of the bell crank lever which turns upon its pivot *f'*¹, and the other arm *f'*² depresses the stem *g* of the ram *g*¹ forcing oil through the passage *j* and past the valves *k* and *l* into the pump cylinder 25 *a*, the parts being so adjusted that the oil is pumped into the cylinder *a* as the piston *b* nears the valve *c*, and after the inlet ports *n* have been covered by the piston. The oil that passes out of the cylinder 30 passes over the lower surface of the casing *o* before again reaching the ram *g*¹.

What I claim is:—

1. In combination a cylinder, a piston in the cylinder, a cylinder cover forming an outlet valve of the cylinder, the top of the piston being shaped to correspond with the underside of the cylinder cover, an inlet port in the cylinder, a ram for supplying oil to the cylinder, means for actuating the ram, a casing inclosing the ram and the ram actuating mechanism, and means for exhausting air from the casing.

2. In combination a cylinder, a piston in the cylinder, a cylinder cover forming an outlet valve of the cylinder, the top of the piston being shaped to correspond with the underside of the cylinder cover, an inlet port in the cylinder, a ram for supplying oil to the cylinder, means for actuating the ram, and a spring controlled valve close to the underside of the cylinder cover through which oil enters the cylinder.

3. In combination a cylinder, a piston in the cylinder, a cylinder cover forming an outlet valve of the cylinder, the top of the piston being shaped to correspond with the underside of the cylinder cover, an inlet port in the cylinder, a ram for supplying oil to the cylinder, means for actuating the ram, a casing inclosing the ram and the ram actuating mechanism, means for exhausting air from the casing, and a spring controlled valve close to the underside of the cylinder cover through which oil enters the cylinder.

4. In combination a cylinder, a piston in

the cylinder, a cylinder cover forming an outlet valve of the cylinder, the top of the piston being shaped to correspond with the underside of the cylinder cover, an inlet port in the cylinder, a ram for supplying oil to the cylinder, means for actuating the ram, and an inlet for oil to the cylinder located between the top of the piston and the cylinder cover after the inlet port has been covered by the piston.

5. In combination a cylinder, a piston in the cylinder, a cylinder cover forming an outlet valve of the cylinder, the top of the piston being shaped to correspond with the underside of the cylinder cover, an inlet port in the cylinder, a ram for supplying oil to the cylinder, means for actuating the ram, a casing inclosing the ram and the ram actuating mechanism, means for exhausting air from the casing, and an inlet 80 for oil to the cylinder located between the top of the piston and the cylinder cover after the inlet port has been covered by the piston.

6. In combination a cylinder, a piston in the cylinder, a cylinder cover forming an outlet valve of the cylinder, the top of the piston being shaped to correspond with the underside of the cylinder cover, an inlet port in the cylinder, a ram for supplying oil to the cylinder, means for actuating the ram, a casing inclosing the ram and the ram actuating mechanism and through which the oil passes from the cylinder to the ram, and means for exhausting air from the casing.

7. In combination a cylinder, a piston in the cylinder, a cylinder cover forming an outlet valve of the cylinder, the top of the piston being shaped to correspond with the underside of the cylinder cover, an inlet port in the cylinder, a ram for supplying oil to the cylinder, means for actuating the ram, a casing inclosing the ram and the ram actuating mechanism and through which the oil passes from the cylinder to the ram, means for exhausting air from the casing, and a spring controlled valve close to the underside of the cylinder cover through which oil enters the cylinder.

8. In combination a cylinder, a piston in the cylinder, a cylinder cover forming an outlet valve of the cylinder, the top of the piston being shaped to correspond with the underside of the cylinder cover, an inlet port in the cylinder, a ram for supplying oil to the cylinder, means for actuating the ram, a casing inclosing the ram and the ram actuating mechanism and through which the oil passes from the cylinder to the ram, means for exhausting air from the casing, 120 and an inlet for oil to the cylinder located between the top of the piston and the cylinder cover after the inlet port has been covered by the piston.

9. In combination a cylinder, a piston in

the cylinder, a cylinder cover forming an outlet valve of the cylinder, the top of the piston being shaped to correspond with the underside of the cylinder cover, an inlet port in the cylinder, a ram for supplying oil to the cylinder, a casing inclosing the ram, a slide on the piston rod, a bell crank lever

actuated by the slide for actuating the ram, and means for exhausting air from the casing.

In testimony that I claim the foregoing as my invention I have signed my name this sixth day of December, 1918.

HENRY ALBERT FLEUSS.
